UNITED STATES PATENT OFFICE.

FRANCIS W. CARPENTER, OF HARRISON, NEW YORK.

TOY LOCOMOTIVE AND CARS.

SPECIFICATION forming part of Letters Patent No. 245,702, dated August 16, 1881.

Application filed June 28, 1881. (No model.)

To all whom it may concern:

Be it known that I, FRANCIS W. CARPENTER, of Harrison, in the county of Westchester and State of New York, have invented an Improvement in Toy Locomotives and Cars, of which the following is a specification.

Toy locomotives have been divided longitudinally into two principal parts, as in Letters Patent No. 228,562, and in other instances made hollow of cast metal, as in Patent No. 227,216.

My present invention relates to the toy locomotive and cars having the peculiarities hereinafter set forth.

In the drawings, Figure 1 is a vertical section of the locomotive and three cars. Fig. 2 is a plan view of the same. Fig. 3 represents a plan view of the body of the locomotive with the top of the cab and the boiler removed, and also a plan view of the cars with awning and wooden bottom removed; and Fig. 4 is a rear elevation of the locomotive.

The wheels and axles *a* and *b* of the toy locomotive are of ordinary character. The main frame *c*, base *e* of the cab, and cow-catcher *d* are cast in one, and there are downward bearings from the frame cast with it, through which the axles pass, and it is preferable to cast the front end piece, *g*, for the boiler at the same time, and in this is an eye, *2*, for the string by which the toy train is drawn along. This piece *g* forms an ornamental covering for the end of the wooden boiler.

The boiler *f* is of wood, and it sets between the end piece, *g*, and the cab, and it is made with a groove that allows the boiler to set down into the half-round forward part, *3*, of the cab. The upper part, *h*, of the cab is made with a similar half-round front end, and when the upper part of the cab is put in place its half-round front end passes into the upper part of the groove in the wooden imitation boiler, and it is held firmly by the screw or rivet *i*, that fastens on the top of the cab to the main frame. The division between the upper and lower parts of the cab is horizontal, and the steadyng-projections on the upper part of the cab pass within the lower part.

The smoke-stack is made of two half-tubes, *l*, riveted together, and the lower ends of the half-tubes may be made with a shank or divided shank, *l'*, passing through the bed of the locomotive and riveted to hold the parts

in place. These half-tubes forming the smoke-stack are of malleable metal, such as malleable cast-iron.

The cars are made with wheels *m*, and cast-metal bodies, with bearings for the axles and end platforms, *4*, as in my Patent No. 227,956; but to render them lighter I make the bottom of the car open-work, cast with the rest of the body, as at *n*, so as to support articles placed in it; and I provide a wooden bottom, *o*, that is either loose or capable of being fastened to close the open-work when desired, said wooden bottom resting at its edges upon the inward metallic flanges, as at *v*.

At the angles of the cars there are corner-pieces *s*, that receive the bows *t*, that are movable and support an awning or top, *r*, over the car. These corner-pieces have vertical holes *70* in them for the reception of the lower ends of the wire awning-bows.

The car may be provided with a platform at one or both ends.

I claim as my invention—

1. In a toy locomotive, the metal frame that supports the boiler, the base of the cab, and the cow-catcher, cast in one piece, substantially as set forth.

2. In a toy locomotive, the metal frame that supports the boiler, the axle-bearings, and the base of the cab cast in one piece, as set forth.

3. In a toy locomotive, the metal frame, with the base of the cab, cast in one piece, in combination with a boiler, of wood or similar material, grooved at its junction with the cab, as specified.

4. In a toy locomotive, the combination, with the metal frame and the base of the cab cast in one, of a top part of the cab connected to the bottom part, and an imitation boiler passed in between the two parts of the cab and held by such cab, substantially as set forth.

5. In a toy locomotive, the combination, with the metal frame, of a wooden boiler and means for connecting the boiler to the frame, substantially as set forth.

6. In a toy locomotive, a cab made in two parts, the division being horizontal, and the upper part connected to the lower part, substantially as set forth.

7. In a toy locomotive, the tubular smoke-stack made of two parts riveted together, substantially as set forth.

8. The combination, in a toy locomotive, of
a tubular smoke-stack, a wooden boiler, a
metal frame, and a metallic connection from
the smoke-stack passing through the boiler
5 and into the frame, as set forth.
9. In a toy vehicle, the metallic body having
bearings for the axle and an open-work metal
bottom, substantially as set forth.
10. In a toy vehicle, a body and end plat-
10 form or platforms of metal, and a wooden bot-
tom introduced within the metal body, sub-
stantially as specified.

11. In a toy vehicle, the combination, with
the metal body and corner-pieces, of removable
wire wagon-bows and an awning or top, sub- 15
stantially as set forth.

Signed by me this 24th day of June, A. D.
1881.

FRANCIS W. CARPENTER.
